BELT ELEVATOR TYPE EDUCATIONAL TOY

Emmet Crawford, 2602 Central Ave., Box 474,
Kearney, Nebr. 68847

Filed Dec. 9, 1974, Ser. No. 531,193

Term of patent 14 years

Int. Cl. D19—07

U.S. Cl. D19—59

FIG. 1 is a front perspective view of a belt elevator type educational toy, embodying my new design;

FIG. 2 is a top plan view thereof;

FIG. 3 is a side elevation view thereof, the opposite side being substantially the mirror image thereof;

FIG. 4 is a bottom view thereof;

FIG. 5 is a front end elevation thereof, as viewed from the left of FIG. 3; and

FIG. 6 is a rear end view thereof, as viewed from the right of FIG. 3.

I claim:

The ornamental design for a belt elevator type educational toy, as shown and described.
